(57) **CLAIM**

The ornamental design for an energy storage system, as
shown and described.

DESCRIPTION

FIG. 1 is a front elevation view of an energy storage system
of our design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof.

This energy storage system is used for storing wind power,
photovoltaic and other clean energy or power peak clipping
and valley filling, etc., and is applied to UPS (i.e. Uninter-
ruptible Power System) power supply, telecommunication
base station energy-storage power supply, etc.
